(57) **CLAIM**

The ornamental design for a biological cell processing chip, as shown and described.

DESCRIPTION

FIG. 1 is an isometric view of a biological cell processing chip showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is an isometric view of the biological cell processing chip in a state of use.

The dashed lines in FIGS. 1-3 depict portions of the biological cell processing chip that form no part of the claimed design. The remaining dashed lines shown in FIG. 8 depict environmental subject matter and form no part of the claimed design.
